UNITED STATES PATENT OFFICE

JOSEPH W. HAWKS, OF SCRANTON, PENNSYLVANIA, ASSIGNOR TO THE WILLIAMS BAKERY, INC., OF SCRANTON, PENNSYLVANIA, A CORPORATION OF PENNSYLVANIA

DESIGN FOR A CAKE

Application filed March 25, 1932. Serial No. 43,290. Term of patent 7 years.

To all whom it may concern:

Be it known that I, JOSEPH W. HAWKS, a citizen of the United States, residing at 1025 Fisk St., city of Scranton, in the county of Lackawanna and State of Pennsylvania, have invented a new, original, and ornamental Design for a Cake, of which the following is a specification, reference being had to the accompanying drawing, forming part thereof.

I claim:

The ornamental design for a cake, substantially as shown.

JOSEPH W. HAWKS.
